FINGER RING

Vincent Sorrentino, Barrington, R. I., assignor to
Uncas Manufacturing Company, a corporation
of Rhode Island

Application May 8, 1953, Serial No. 24,926

Term of patent 14 years

(Cl. D45—10)

To all whom it may concern:

Be it known that I, Vincent Sorrentino, a citizen of the United States of America, residing in Barrington, county of Bristol, State of Rhode Island, have invented a new, original, and ornamental Design for a Finger Ring, of which the following is a specification, reference being had to the accompanying drawing, forming a part thereof:

Fig. 1 is a front elevational view of a finger ring showing my new design;

Fig. 2 is a top plan view thereof; and

Fig. 3 is an edge view thereof.

The dominant part of the design is shown in full lines.

I claim:

The ornamental design for a finger ring, substantially as shown and described.

VINCENT SORRENTINO.
